Howard & Howard.

UNITED STATES PATENT OFFICE.

OSCAR A. EASTLACK, OF CAMDEN, NEW JERSEY.

LOCK AND LATCH.

Application filed November 28, 1921. Serial No. 518,192.

My invention relates to improvements in locks and latches, the object of the invention being to provide improved means for preventing the picking of the lock as by means of forcing back the bolt with a sharp instrument inserted between the lock and the keeper plate.

The invention will be more readily understood by reference to the attached drawings, 10 in which:

Figure 1 is a rear face view of a lock made in accordance with my invention, having the cover plate removed;

Fig. 2 is a section on the line 2—2, Fig. 1;

Fig. 3 is a view similar to that of Fig. 1, but illustrating the bolt in the retracted position, and

Figs. 4 to 10, both inclusive, are detached perspectives of elements of the lock mechanism.

In the drawings, 1 indicates the lock casing comprising a substantially rectangular trough-shaped portion 2, said casing having detachably secured thereto in suitable manner a cover plate 3 for the open side of the casing. Mounted in one end of the casing is a knob 4 having attached thereto on the inside of the casing, as best shown in Fig. 1, a substantially T-shaped element 5, by means 20 of which the bolt is retracted when the knob is turned in a manner to be described hereinafter. In alignment with the knob 4 and fixed in the cover plate 3 is a key-operated shaft 6, to the inner end of which a second substantially T-shaped element 7 is secured, said element being adapted in the same manner as the element 5 for retracting the bolt.

Slidably mounted in the front of the casing 1 and adapted to extend through a suitable opening in the front side thereof is a bolt 8, said bolt having a pair of rearward extensions 9 and 10, as most clearly shown in Fig. 4, and said extensions being so shaped as to provide a lateral slot or recess 11. Projecting rearwardly from the ends of each of the projections 9 and 10 is a tail-piece or guide pin 12, 12, which latter pass through suitable apertures in a guide plate 13 mounted on and extending between a pair of bracket lugs 14, 14, which extend inwardly from the base of the casing 1, the guide pins being free to slide through said apertures. Extending through a central aperture or passage 15 in the bolt 8 and extending rearwardly intermediate the said extensions 9 and 10 of said bolt and through a suitable

aperture in the guide plate 13, is a trip or release pin 16, said pin having secured to the inner end thereof a substantially U-shaped cross head 17. The outer ends 18, 18, of this cross head are turned laterally away from each other and are widened so as to permit of engagement by the respective arms of the two retracting elements 5 and 7, as best shown in Figs. 1, 2 and 3.

Secured to the pin 16 is a cross head 20, said cross head extending upwardly between the extensions 9 and 10 of the bolt and having laterally extending arms 21, 21, established in the recess 11 in the said bolt. 70 Mounted on the pin 16 and confined between the guide plate 13 and the inner face of the cross head 20 is a spring 22, while each of the guide pins 12 also carries a spring 23 which are confined between the guide plate 13 and the rear faces of the extensions 9 and 10. The springs 22 and 23 tend to retain both the bolt and the pin 16 in the advanced position in which they are illustrated in Figs. 1 and 2. It will be apparent that the pin 16 is permitted a movement independent of the bolt 8 to the extent of the difference in width between the slot 11 and the arms 21 of the cross head 20, and further that when either of the retracting elements 5 or 7 is moved to retract the bolt, there results first a movement to the full extent of the pin 16 independent of the bolt or until the rear faces of the arms 21, 21, engage the rear face of the slot 11, after which the bolt 8 is withdrawn with the pin 16 to the final position illustrated in Fig. 3. The inward movement of the bolt is limited by a pair of lugs 3^a on the cover plate 3, said lugs being located respectively in the paths 85 of the projections 9 and 10.

In the retracted position of the bolt 8, a detent 25 slidably mounted in the base of the casing is adapted to releasably retain the bolt, said detent having a forwardly extending hook-like member 26, which latter is adapted to engage the forward end of the extension 9 of the bolt, as illustrated in Fig. 3. A pin 27 extends through a slot in the base of the casing 1, and is secured to the detent 25 in the manner shown in Fig. 2, said pin having a shoulder bearing against the outer surface of the casing, thereby both retaining the detent in proper position between sets of guide lugs 28, 28, on the inside 110 of the casing and providing means for shifting the detent to either engage or release the

2
bolt; as the case may be, from the outside of the casing. The rear edge of the detent 25 has therein a pair of notches 30, 30, which notches are adapted to be engaged by the 5 forward tapered end of a pin 31 slidably mounted in an opening in a lug 32 extending inwardly into the casing 1 from the base thereof, there being confined between the rear of the pin 31 and the inner end of the 10 recess in the lug 32 occupied by the pin, a spring 33 tending to force the pin forwardly against the rear notched edge of the latch 25, said pin and spring functioning to retain the latch in either the bolt-retaining or bolt- 15 releasing position, as the case may be.

Extending inwardly from each side of the casing 1 and mounted in suitable guide brackets 35, 35, is a locking pin 36, said pins being slidably mounted in suitable slots 37 20 in said brackets, and being retained in the slots by the cover plate 3, as best shown in Fig. 2. Each of the locking pins is recessed at the rear and has established in said recess a pin 38, between the inner end of which 25 and the bottom of the recess is confined a spring 39, which latter tends, by forcing the pins 38 against the sides of the casing, to advance the locking pins inwardly in their slots, the inward movement of the locking 30 pins being limited by shoulders 40 at the rear thereof which engage the sides of the brackets 35, as shown in Fig. 1. In this figure, the locking pins are illustrated in the normal advanced position, in which position the forward edges lie in back of the inner ends of the extensions 9 and 10 of the bolt 8, thereby preventing retraction of the bolt. Means, however, is provided comprising a cam plate 41 secured to the top of the 35 cross head 20 for forcing the pins outwardly to release the bolt upon retraction of the pin 16, the cam element 41 having rearwardly extending arms 42, 42, the beveled rearward end edge of which is adapted 40 to engage similarly beveled portions 43 of the forward edges of the locking pins 36, the interaction of these engaging beveled portions effecting an outward movement, when the pin 16 is retracted, of the said locking pins 36, and a consequent release by said locking pins of the bolt 8.

It will be noted that the independent movement of the cross head 20 and the pin 16 independent of the bolt is sufficient to accomplish the retraction of the locking pins 36 to a sufficient extent to release the bolt 8, which thereafter is permitted to move rearwardly with the pin 16. It will be noted also that the front corners of the cam member 41 are beveled, as indicated at 45, 45, and that the locking pins 36 also have a portion 46 of their rear inner edges beveled to correspond with the bevel 45, these bevels insuring under all conditions a withdrawal of 5 the locking pins to permit the advance of

the bolt into the operative position from the retracted position.

In conjunction with the elements of the lock so far described, there is provided a keeper plate 48 for the bolt 8, said plate including an extension 49 from one side having a beveled or inclined face 50. The casing 1 may be attached to the door in the usual manner, and the keeper plate to the door jamb in a position to receive the bolt 8 when the door is closed. In closing the door, the beveled face 50 of the keeper plate is engaged first by the beveled forward end of the pin 16, which extends beyond the correspondingly forward beveled face of the latch 8, the pin 16 accordingly being forced into the casing to a sufficient extent to retract the retaining pins 36, and to thereby release the bolt 8. When, therefore, the beveled face of the bolt engages the inclined face 50, the bolt is free to move into the casing 1, which it accordingly does, both the bolt and the pin 16 being forced out of the casing 1 and into the interior of the keeper plate 48 after the door is closed by means of the springs 22 and 23. In this position, it is manifestly impossible to again retract the bolt 8 until the pin 16 is first retracted, and since retraction of this pin can be accomplished only by means of the knob 4 or by a key through the sleeve 6, all danger of the lock being picked is eliminated.

It will be noted that the locking device hereinbefore described is of an extremely simple and efficient nature, and in no way interferes with the normal operation of the bolt when the door is thrown to. It should further be noted that the bolt 8 is symmetrical about a horizontal plane (reference being had to Fig. 2) passing through the center of the pin 16, thus permitting inversion of the bolt without effecting the operation of the lock. In this manner, the lock may be adapted for use on doors which open outwardly as well as inwardly.

Although the particular lock illustrated and described is what is termed a "rim" lock, this particular type of lock was selected entirely for the purpose of illustration, and it is obvious that my invention is not limited thereto.

I claim:

1. The combination with a casing of a bolt slidably therein and adapted in an advanced position to project beyond the side of said casing, a single retracting element slidably within said bolt in a direction coincident with the movement of said bolt and normally projecting beyond the face of said bolt, means for limiting the relative movement between the retracting element and the bolt, and means engaging said retracting element for effecting initial relative movement between the retracting element and the bolt and subsequent con-

current movement of the retracting element and the bolt, to effect retraction of the bolt to a position within the casing.

2. The combination with a casing, of a bolt slidable in said casing and adapted in an advanced position to project beyond the side thereof, an element movable with respect to and in a direction paralleling the path of the bolt, means on the bolt limiting the movement of said element relative to the bolt, means connected with the element for shifting the bolt to a retracted position within the casing, and movable means projecting into the path of and normally preventing retraction of the bolt and adapted to be shifted out of the path of the bolt by said relatively movable element.

3. The combination with a casing, of a bolt slidable in said casing and adapted in an advanced position to project beyond the side of the casing, means within the casing tending to prevent the retraction of the bolt from the advanced position, an element movable with respect to and slidable in a direction paralleling the path of the bolt and adapted to release the bolt from the said retraction-preventing means, means on the bolt limiting the movement of said element relative thereto, and bolt retracting means connected with said element.

4. The combination with a casing, of a bolt slidable therein and adapted in an advanced position to project beyond the side of the casing, a lateral recess in said bolt, a member mounted in said recess and having therein a limited movement relative to the bolt, bolt retracting means connected to said element, and elements adapted to project into the path of said bolt to prevent retraction and to be shifted out of the path of said bolt by movement of the said member.

5. The combination with a casing, of a bolt slidably mounted therein and adapted in an advanced position to project beyond the side thereof, a spring-pressed dog movably mounted in the casing and adapted normally to project into the path of the

bolt to prevent retraction from the advanced position, and means operatively associated with the bolt and having a limited movement relative thereto for shifting said retaining element from the path of the bolt to permit retraction of the latter into the casing.

6. The combination with a casing, of a bolt slidably mounted in said casing and adapted in an advanced position to project beyond the side thereof, a spring-pressed element adapted normally to project into the path of said bolt to prevent retraction of the latter from the advanced position, a member operatively associated with and having a limited movement relative to the bolt and having an inclined cam surface adapted to engage the bolt-retaining element to shift it by movement of the member from the path of the bolt when the latter is retracted, and retracting mechanism connected with said member.

7. The combination with a casing, of a bolt slidably mounted in the casing and adapted in an advanced position to project beyond the side thereof, an element extending through said bolt and normally beyond the outer face thereof and being capable of limited movement relative to the bolt, retracting mechanism connected with said element, means for releasably retaining the bolt in the advanced position, and means carried by said element for releasing the bolt from said retaining means to permit retraction into the casing.

8. The combination with a casing, of a bolt slidably mounted in the casing and adapted in an advanced position to project beyond the side thereof, an element extending through said bolt and normally beyond the outer face thereof and being capable of limited movement relative to the bolt; the center line of said element lying in a plane bisecting the bolt whereby reversal of the bolt in the casing is permitted, and retracting mechanism connected with said element.

OSCAR A. EASTLACK.
